(57) **CLAIM**

We claim the ornamental design for a compact spotting scope, as shown and described.

DESCRIPTION

U.S. Utility Patent Application titled Compact Spotting Scope With Side Focus Control, filed concurrently under Ser. No. 10/425,057.

FIG. 1 is a perspective view of a compact spotting scope in accordance with a first embodiment;

FIG. 2 is an objective end elevation view of the compact spotting scope of FIG. 1;

FIG. 3 is an eyepiece end elevation view of the compact spotting scope of FIG. 1, in which dashed lines indicate environmental features of surface indicia near the eyepiece end of the compact spotting scope;

FIG. 4 is a top plan view of the compact spotting scope of FIG. 1;

FIG. 5 is a left side elevation view of the compact spotting scope of FIG. 1;

FIG. 6 is a bottom plan view of the compact spotting scope of FIG. 1; and,

FIG. 7 is a right side elevation view of the compact spotting scope of FIG. 1.

In FIGS. 1–7, the dashed lines indicate environmental features that form no part of the embodiments of the invention.
